UNITED STATES PATENT OFFICE.

JAMES C. MAHAN, OF LINCOLN, NEBRASKA.

WIRE-FENCE TOOL.

1,143,414.

Specification of Letters Patent. Patented June 15, 1915.

Application filed June 18, 1912. Serial No. 704,345.

To all whom it may concern:

Be it known that I, JAMES C. MAHAN, a citizen of the United States, residing at Lincoln, in the county of Lancaster and State 5 of Nebraska, have invented new and useful Improvements in Wire-Fence Tools, of which the following is a specification.

The present invention relates to improvements in tools employed in erecting wire 10 fences:

In carrying out my invention I propose to provide a tool, in the nature of a pair of pliers which is provided with simple but effective means for stretching a wire around 15 a post, for cutting the wire or for forming loops upon the wire.

I further aim to provide a tool of this class with a rotatable head which is provided with means for grasping a wire and 20 which, upon the movement of the handles and jaws of the device will rotate the said head to twist the wire upon the head either to stretch the wire or to form a loop upon the wire.

I further aim to provide an instrument of 25 this class having a head made up of a pair of sections, one being of a greater size than the other, and whereby the said sections may be readily removed from between the jaws 30 of the pliers to receive the wire and may be easily and quickly reinserted between the jaws, the said head being formed with teeth, and one or both of the jaws of the pliers being provided with lugs or projections 35 which are adapted to co-act with the teeth of the head when the jaws are opened and closed, so as to rotate the said head, step by step, to operate upon the wire.

With the above recited objects in view, 40 and those which will appear as the nature of the invention is disclosed, the invention resides in the construction, combination and arrangement of parts set forth in the specification and falling within the scope of the 45 appended claims.

In the drawings, Figure 1 is a perspective view of an implement constructed in accordance with the present invention. Fig. 2 is a similar view of the pliers portion, the 50 head being removed. Fig. 3 is a perspective view of one of the members of the head. Fig. 4 is a similar view of the second member of the head. Fig. 5 is a transverse sectional view taken centrally of the head 55 when the members comprising the said

head, are assembled. Fig. 6 is a similar sectional view taken through the upper portion of the head or that through which the wire is passed. Fig. 7 is a view illustrating the method of operating the implement in 60 connection with a post. Fig. 8 is a view of one of the wire loops formed by the implement.

Referring to the drawings in detail the numeral 1 designates my improved implement. The device contemplates primarily the employment of a wrench or plier-like structure, the same embodying a pair of handles 2 and 3 having reduced rounded portions which are pivotally connected together as at 4 and which are extended to provide the oppositely arranged jaws 6 and 7, having their co-acting faces inwardly curved, and the portions of the jaws adjacent said curved inner edges are provided 70 with teeth 8. The rounded reduced portions through which passes the pivot 4 are provided with slots or depressions 9 and 10 which have their edges sharpened and which are adapted to serve as wire cutting elements, as will be readily understood. The teeth 8 are adapted to serve as wire gripping surfaces, and both the handles 2 and 3 adjacent said pivoted portions are also provided with teeth 11 and 12 which likewise serve as wire gripping members. Connected with the handles 2 and 3 is a suitable spring 13 which is adapted to bring the jaws 6 and 7 together for the closing thereof. One or both of the jaws adjacent their 75 inner curved edges are provided upon their faces with lugs 14, the purpose of which will presently be set forth.

The numeral 15 designates what I term the head, for the jaws. This head embodies 80 a pair of members designated respectively, by the numerals 16 and 17. The member 16 is rounded in cross section and preferably is in the form of three-fourths of a circle. This member is provided with a rounded bore 18 and the faces or edges of the said member communicating with the bore, are inclined from their outer edges toward the said bore 18, as indicated 85 by the numerals 19. The member 16 is provided on the outside with a centrally reduced portion to receive the plier jaws and has its opposite ends or faces formed with a plurality of teeth 20 and 21. One of the inclined edges 19 is provided with a spring 100 105 110

22, the purpose of which will presently be set forth. The member 17 is cross sectional of a quarter of a circle and the said member is provided with a bore 23 which is adapted 5 to register with the bore 18 of the member 16 when the sections are assembled. The member 17 is centrally reduced and formed at opposite ends with teeth 24, and is further formed adjacent one extremity with an 10 opening 25 communicating with the bore of the member 17 and another opening 26 extending transversely through the member 17 and communicating with both the bore 23 and the opening 25.

15 The member 16, adjacent its inclined edges or faces 19 is further provided with depressed portions 27, the latter extending the full length of the bore 18, and the member 17 is provided with what may be termed 20 ribs 28, which are arranged adjacent its inclined edges 29 and which are adapted to be received within the depressions 27, while the said inclined faces 29 are adapted to contact with the inclined faces 19 of the members 25 16, when the members are assembled. One of the inclined faces 29 of the member 17 is provided with a depression 30, the latter adapted to receive the upper offset portion of the spring 22 to lock the members 30 16 and 17 together.

By constructing the head and sections as above described, it will be readily noted that the said sections may be easily inserted between the jaws 6 and 7 of the wrench or 35 pliers. Furthermore, the sections may be readily separated and a wire may be passed through the bore provided by the said sections and passed through either the opening 25 or the opening 26 of the section 17 of the 40 head, which after being replaced within the jaws of the wrench or pliers may be brought around a post as illustrated in Fig. 7 of the drawings, or coiled to provide a loop. It will be noted that there is always a tension 45 upon the wire 31 which tension is sufficient to hold the head, irrespective of the movement of the handles 2 and 3 of the pliers. By revolving the pliers, the lugs 14 being in engagement with the teeth of the head will 50 likewise rotate the said head. When the pliers have been rotated a suitable or convenient distance, the handles thereof may be swung away from each other to open the jaws, the head in the meantime being retained under the tension of the wire, and 55 thus permitting the tool to be returned to its initial or to a more convenient position. When the jaws have been brought to their closed position they will be arranged so that 60 their lugs 14 will engage additional teeth provided upon the head, so that the pliers

really provide a ratchet movement for the head.

From the above description taken in connection with the accompanying drawings, it is thought that the utility of the device, and the simplicity thereof as well as its advantages will be fully understood by those skilled in the art to which such inventions appertain, without further detailed description.

Having thus described the invention, what I claim as new is:—

1. In a device for the purpose set forth, a pair of members pivotally connected together and including handles and jaws, a spring between the handles for normally holding the jaws close to each other, the said jaws being provided with lugs, an independent head member arranged between the jaws, said head member comprising a pair of sections, one of a greater cross-sectional area than the other section, spring means for connecting the sections, both of the sections being provided with a wire-receiving bore, one of the sections having angularly arranged wire passages, the face of the head being provided with teeth, and the said teeth adapted to co-act with the lugs provided on the jaws of the first-named member.

2. In a device for the purpose set forth, a tool having its jaws provided with lugs, an independent and removable head between the jaws, said head embodying a pair of sections which when matched form a tubular member, one section being of a greater cross-sectional area than the other, the meeting faces of both of the sections being inclined, both of the sections being provided with rounded bores, one of the sections having its bore formed adjacent its inclined faces formed with depressions communicating with its bore, the second section being provided with ribs which are adapted to be received within the said depressions, one of the sections being provided with a spring latch, the second section being provided with a depression adapted to receive the latch, one of the sections having an angularly arranged wire passage communicating with its bore, the head having its faces provided with teeth, and the said teeth adapted to co-act with the lugs upon the jaws of the tool, substantially as and for the purpose set forth.

In testimony whereof I affix my signature in presence of two witnesses.

JAMES C. MAHAN.
